UNITED STATES PATENT OFFICE.

THOMAS HOOLEY, OF STOCKPORT, ENGLAND.

PROCESS OF BLOCKING IN GOLD AND OTHER METALLIC LEAF.

1,155,574.

Specification of Letters Patent.

Patented Oct. 5, 1915.

Original application filed April 10, 1912, Serial No. 689,736. Divided and this application filed July 1, 1912.
Serial No. 706,875.

To all whom it may concern:

Be it known that I, THOMAS HOOLEY, a subject of the King of the United Kingdom of Great Britain and Ireland, residing at 5 Duke street, Stockport, in the county of Chester, England, have invented new and useful Improvements in Blocking in Gold and other Metallic Leaf, of which the following is a specification.

10 This invention relates to blocking in gold and other metallic leaf, and it has for its object to enable blocking of this class to be more satisfactorily effected in blocking presses than has heretofore been possible.

15 To avoid unnecessary repetition the term "gold leaf" is herein used to include gold leaf, silver leaf and leaf of any other metal, wherever the context admits of such a meaning being attributed to it.

20 Owing to the extreme delicacy and buoyancy of gold leaf, the blocking in this metal involves the exercise of extreme care first in applying it to the die of a blocking press and secondly after it has been so applied in 25 preventing it from being wafted off the die before it has been deposited on the surface to be blocked.

Presses have heretofore been proposed for mechanically blocking in gold leaf but none 30 of them have proved satisfactory owing to the fact that the dies, after having the gold leaf attached to their surfaces, have been moved in directions parallel with said surfaces so that the gold leaf has been 35 wafted off the dies by the air currents to which it was thereby subjected.

In all blocking presses heretofore designed for use in blocking with gold leaf, the dies, with the gold leaf attached thereto, 40 have, after such attachment, been moved in directions other than perpendicular to their blocking faces and have thereby subjected the said gold leaf to air currents which have been causative of its detachment from 45 the face of such dies.

The present invention differs from all former processes in respect of the fact that it involves no such movement of the dies as would expose the gold leaf to air currents that would tend to detach the said gold leaf from the dies, from the time that the gold leaf is attached to their surfaces to the time that it is deposited on the articles to be blocked.

50 55 In carrying out the process according to

my invention, I employ a press which, according to a patent application from which the present one has been divided, is provided with a movable tray or magazine for containing a book, or two or more superimposed books (hereinafter referred to as a pile), of gold leaf, these books having the usual interleaving paper sheets between adjacent metallic sheets. This tray is capable of being moved into and out of position beneath the die, and the process constituting the subject matter of the present application may be said to consist in first greasing the blocking surface (which is heated in any of the known ways), then bringing the top sheet of the pile of gold leaf and the greased surface, lightly into contact either with the other so as to cause the former to adhere to the latter, then moving the pile of gold leaf away from the die or the die, 65 in a direction perpendicular to its own face, away from the said pile, so as to separate the leaf adhering to the die from the others in the pile, next removing the said pile from beneath the die and then forcing the previously prepared surface to be blocked, against the die or the die in a direction perpendicular to its own face against the said surface so that upon the subsequent separation of the die and that surface, the gold leaf will 80 be left adhering to and impressed into the latter.

A press suitable for carrying out the process, the subject of the present invention, is shown by way of example in the accompanying drawings in which—

Figure 1 is an end elevation and Fig. 2 a side elevation of a well-known form of blocking press arranged for enabling the process to be carried out, and Fig. 3 is a 95 diagrammatic plan view showing the die and the tray supporting the gold leaf, in its normal or inoperative position in full lines, and in its working position in dot-and-dash lines.

In the press illustrated in these drawings, the main structure comprises the two side frames 1, 2, united at their lower ends by tie bars 3, 4, and at their upper ends by a bridge 5.

The frames 1, 2, are provided with guides 6, 6, whereon is capable of sliding in a vertical direction, a bed 7 provided with horizontal tracks 8 whereon is capable of sliding in a horizontal direction, a table 9, the 110

latter being moved along the said tracks manually as by means of a handle 10. The bed 7 receives vertical motion in one direction by cams 11 fast to a shaft 12, on one end of which is secured a hand lever 13, the arrangement being such that when this hand lever is in the vertical position in which it is shown in the drawings, the bed 7 and all the parts carried thereby, will be in their lowest position, and when the said hand lever 13 is moved out of this position, say, toward the left in Fig. 2, then the said bed and parts carried thereby, are raised by the cams 11, the subsequent lowering of the said parts being effected by gravity when the hand lever 13 is returned to its normal vertical position.

The before mentioned bridge 5 carries beneath it, a block 14 adapted, in well-known manner, to be heated by gas or other means, to which is attached as ordinarily, the die 15 bearing the design to be blocked in gold leaf.

Attached to one side of the bed 7 is a bracket 16 adjustably held thereto by bolts, nuts and slots 17, the said bracket being adapted to participate in all of the vertical movements of the bed. The upper end of the bracket 16 terminates in an outwardly-extending arm 18 to which is pivoted a plate or tray 19 capable of being swung from the position in which it is shown in full lines in the drawings (in which position the ascent of the bed will not bring the said tray into contact with the die 15), into the position in which it is represented in dot-and-dash lines, in which (see particularly Fig. 3) the ascent of the bed will cause the tray or the pile of gold leaf thereon to be brought into contact with the face of the die. The tray 19 may be moved from one to the other of the two just-named positions by means of a handle 20, or other suitable device.

The tray 19 is provided for the purpose of supporting a pile of gold leaf 21 (see particularly Figs. 2 and 3), the underside of this pile, if desired, being attached to the tray 19 by paste or equivalent adhesive and retained in position on the tray by gages 22.

A book of gold leaf as generally supplied to the user, is bound together at one edge, but, for the purpose of this invention, that edge is cut off and the cut edge of the book thus presented, is preferably smeared over with adhesive cement such as paste or thin glue so as to prevent the accidental detachment from the book of more than one leaf at a time.

At the end of the table 9 opposite to that at which the handle 10 is provided, there is adjustably carried a grease roller 23, this being supported in columns 24 vertically adjustable by screws 25 in two brackets 26 (only one of which is shown in the drawings) rigidly attached to the adjacent end

of the table 9. The grease roller 23 is adjusted by the screws 25 into such position that during its forward and backward horizontal motion along with the table 9, its periphery will rub under the surface of the die 15 so as to leave a thin deposit thereon of the grease carried by the said roller.

In carrying out the process according to the present invention, the operator first removes the uppermost sheet of the pile to expose a leaf of gold, and greases the heated die 15 by traversing the grease roller 23 beneath it as previously described, the table 9 and the roller 23 being thereafter left in their rearmost position, that is to say, the position in which they are shown in Fig. 2. The operator then swings the tray 19 with the pile of gold leaf 21 thereon, beneath the die 15 and thereafter depresses the lever 13 so as to raise the bed 7 and with it the tray 19, and by those means, bring the topmost leaf of gold into contact with the greased face of the said die. The lever 13 is then raised to its normal position allowing the bed 7 and tray 19 to descend by gravity and in so doing, withdraw the pile of gold leaf 21 away from the die, leaving the topmost leaf of gold from this pile attached to the greased face of the die. The tray 19 with the pile of gold leaf thereon, is then swung from beneath the die into the position in which it is shown in full lines in the drawings, (see particularly Fig. 3), and thereafter the table, with the case or material to be blocked previously positioned thereon and previously glaired or prepared for receiving the impression, is raised into forcible contact with the heated die 15 by means of the hand lever 13. The lever 13 is then again returned to its normal vertical position and the table 9 with the blocked case or material thereon, is allowed to descend, the table thereafter being moved along the tracks 8 from beneath the die 15, for the removal therefrom of the blocked case or material and the substitution therefor of the case or material to receive the next impression which latter will be given by a repetition of the previously described series of operations.

In a power press, it may be convenient to have the before mentioned tray provided with a spring-supported floor which will oppose the pressure of the pile of gold leaf against the die with a pressure sufficient to cause the top leaf of the pile to adhere to the die (whatever the quantity of gold leaf supported on that floor) without damaging the lower sheets of the said pile.

It will be understood that so far as the carrying out of the improved process is concerned, it is immaterial whether the pile of gold leaf be moved perpendicularly to its surface into contact with the die, or the die be moved perpendicularly to its surface into contact with the pile of gold leaf, this last

named manner of operation depending upon whether the press is one of the known type in which the work is moved to the die, as in the before described example, or one of another known type in which the die is moved to the work.

Having described my invention, I declare that what I claim and desire to secure by Letters Patent is:—

10 The process of blocking in gold leaf consisting in greasing the face of a die, pressing a sheet of gold leaf on to the die, press-

ing the surface of the article to be blocked against the face of the die, and maintaining the die stationary from the time gold leaf 15 is applied to it until that leaf is impressed on the article to be blocked.

In witness whereof, I have hereunto set my hand in the presence of two witnesses.

THOMAS HOOLEY.
